UNITED STATES PATENT OFFICE.

RAYMOND J. FRANCIS, OF GIBBON, NEBRASKA.

HAY LOADER AND STACKER.

1,121,821.

Specification of Letters Patent. Patented Dec. 22, 1914.

Application filed June 8, 1912. Serial No. 702,478.

To all whom it may concern:

Be it known that I, RAYMOND J. FRANCIS, a citizen of the United States, residing at Gibbon, in the county of Buffalo and State 5 of Nebraska, have invented certain new and useful Improvements in Hay Loaders and Stackers, of which the following is a specification, reference being had therein to the accompanying drawing.

10 This invention relates to hay loaders and stackers and has for its object the production of an efficient means whereby the hay may be lifted and automatically dumped after the frame has been swung to the desired position.

15 Another object of this invention is the production of an efficient tripping means for controlling the swinging movement of the crane.

20 With these and other objects in view this invention consists of certain novel constructions, combinations, and arrangements of parts, as will be hereinafter fully described and claimed.

25 In the drawings: Figure 1 is a side elevation of the hay loader and stacker. Fig. 2 is a top plan view of one-half of the stacker. Fig. 3 is a top plan view of the frame comprising a hay stacker. Fig. 4 is a side elevation of the return spring, and means for attaching the support for said return spring to the main standard. Fig. 5 is a longitudinal section through the rear end of the hay lifting fork. Fig. 6 is a fragmentary trans-

35 verse section through the hay lifting fork. Fig. 7 is a transverse section through the standard pipe or main standard. Fig. 8 is a transverse section through the main standard or standard pipe showing the manner of bracing or connecting the return spring and support to the standard pipe. Fig. 9 is a transverse section through the collar which carries the ratchet device for locking the crane in its adjusted swinging

45 position. Fig. 10 is a transverse sectional view through the casing which supports the latching device for locking the crane in an adjusted position. Fig. 11 is a top plan view of the apparatus which returns the

50 teeth and automatic trip regulator upon the frame of the machine. Fig. 12 is a side elevation of the device as illustrated in Fig. 11. Fig. 13 is a transverse section of the stop switch which determines the number of 55 dumps of the fork. Fig. 14 is a longitudi-

nal section of the switch. Fig. 15 is a side elevation of the journal plate carried by the crane and through which the journal pin passes. Fig. 16 is a front elevation of the hay lifting fork. Fig. 17 is a front view 60 of the pulley blocks carried by the hay lifting fork and the outer end of the crane over which the lifting cable passes. Fig. 18 is a top plan view of the supporting casting which encircles the main supporting standard. Fig. 19 is a front elevation thereof. Fig. 20 is a front view of the supporting casting through which the rack member of the automatic trip regulator passes. Fig. 21 is a perspective view of the sliding shoe adapted 65 to work upon the rack bar as illustrated in Fig. 12. Fig. 22 is a transverse section through the rack bar and sliding shoe showing the manner of supporting the sliding shoe in engagement with the rack bar. 75

The present machine is adapted for the purpose of loading hay or the like and comprises a frame which consists of a pair of side members 1 converging toward their rear ends and being secured together by 80 means of a transverse cleat 2. The forward end of the side members 1 are connected by means of a transverse beam 3. A central supporting beam 4 extends transversely of the beams of the side members 2 and constitutes a support for the main standard 5. Divergent braces 6 are connected centrally 85 of the transverse beams 4 and have their outer ends engaging the transverse beam 3 near its respective ends. The frame is supported by means of wheels 7, which wheels 7 are journaled upon stub axles 8, which axles 8 are held in engagement with the transverse beam 3 by means of journals or 90 boxings 9. Skidding shoes 10 are carried 95 near the converging ends of the side members 1 of the frame and constitute supports for the front end of said frame. This structure is clearly illustrated in Fig. 1.

A supporting casting 11 is carried by the 100 main standard 5 near its upper end and this supporting standard is provided upon one side with a depending sleeve 12 which sleeve receives a forwardly extending brace 13. This brace 13 has its lower end positioned 105 within a casing 14, which casing 14 is carried by the transversely extending beam 2. The casting 11 is also provided with a pair of divergent socket portions 15, which portions receive the diverging braces 16, which 110

braces have their lower ends connected to the rear corners of the frame or the rear ends of the side members 1.

A crane 17 is carried by the main standard 5, and this crane carries a collar portion near its upper end which is provided with laterally extending sockets for receiving a journal pin adapted to constitute a bearing upon which the crane is to operate. The crane 17 comprises a pair of upper and a pair of lower longitudinally extending angle members which members are connected by vertically extending truss braces 18 which braces are placed at intervals throughout the entire length of the crane 17. The longitudinally extending members of the crane 17 are also braced by means of transversely extending braces 19, and cross braces 20 for constituting a very rigid structure to withstand the weight of the lifting fork, and the hay which is adapted to be lifted thereby.

A journal plate 21 is carried by the inner face of the crane and upon each side of the standard 1 and this plate 21 carries a pair of oppositely extending parallel arms 22 which arms 22 are firmly secured to the longitudinally extending parallel portions of the crane 17, the central web portion 23 being secured to the journal pin 24 which journals the crane upon the main standard 1. A lifting frame 25 is associated with the crane 17 and comprises a pair of side members 26 which converge near their upper ends and are secured to the journal pin 24 previously mentioned. These side members 26 carry at their upper ends spacing cleats 27 which cleats are provided with beveled faces adjacent the side members 26 so as to form a flat surface to engage the crane and also form a flat surface to be engaged by the nut or head of the shaft 24. The side members 26 of the frame are braced against spreading movement by means of cross braces 28, and to the outer ends of the side members 26 is connected the hay lifting fork 29. This fork 29 is, of course, secured to the ends of the frame 26 so as to allow the fork to swing downwardly whereby the hay may be dumped from the fork.

A stop frame 30 is carried by the lifting fork 29, and is braced by means of converging braces 31. A lifting brace 32 is carried by the hay lifting fork 29, and this brace terminates in an eye 33, which is connected to the lifting pulley 34, hereinafter described. The lifting fork 29 is journaled upon the transversely extending shaft 35, and the stop frame 30 is braced by means of metallic braces 36, said braces terminating in eyes 37 at their upper ends for receiving the angle stub shafts 38 of the tilting brace arms 39. These brace arms 39 are provided with outwardly extending stub shafts 38.

The upper ends of the tilting brace arms 39 are brought together and firmly clamped thereby forming a substantially V-shaped structure as indicated in Fig. 16. A bracing cable 40 is secured to the tilting brace arms 39 and between these tilting brace arms is placed a connecting member which may be adjusted between the brace arms for adjustably connecting the cable 40 to the brace arms 39. This cable 40 passes over a pulley 41 at the upper end of the main standard 5, and this cable passes down through the main standard 5, and over the pulley 42, which pulley is journaled upon a clamping band 43 carried by the main standard 5. This cable is in turn attached to a sliding head 44, which sliding head 44 works upon the auxiliary vertical shaft 45. The lower end of the shaft 45 is connected or supported by means of a bracket 46, which bracket is fixedly secured to the main standard 5. This bracket 46 projects laterally from the standard 5, and is provided with a downwardly turned end 47, which terminates in a laterally extending end 48, as illustrated in Fig. 8. A clamp 49 is connected to the main standard 5, and also grips the vertical shaft 45. The head 44 is held in engagement with the clamp 50 by means of a coil spring 51, and this clamp 51 carries a pawl 52 having a gripping end 53. The gripping end 53 overhangs the lower edge of the sliding head 44, and normally holds the head against sliding movement upon the shaft 45. A spring 54 is carried by the bracket 50, and engages the pawl 52, and this pawl 52 is connected to a vertical sliding rod 55 as indicated at 56. This rod 55 is adapted to have vertical sliding movement and as the rod 55 is moved downwardly, it will be seen that the dog or pawl 52 will be drawn away from the head 44, and the head will be allowed to slide upon the shaft 45, as pressure is brought to bear upon the cable 40. This rod 55 is connected to a lever 57, which lever is pivotally secured to the bracket 46 as at 58. A roller 59 is carried by the outer end of the lever 57, and this roller is adapted to be lifted by a mechanism hereinafter described, whereby the vertical sliding rod 55 will be operated to move downwardly thereby causing the pawl 52 to be released from the sliding head 44.

A drum supporting casing or bracket 60 is fixedly secured to the main standard 5, and is provided with a pair of parallel arms 61 between which is journaled the winding drum 62. This winding drum 62 is provided with a shank 63, which shank is adapted to receive a crank for allowing the drum to be operated, whereby the crane 17 may be swung to its correct horizontal position. A cable 64 is wound around the drum 62 and has its upper end connected to

the forward end of the crane 17 by means of a hook 65. The drum supporting casing or bracket 60 is provided with a rearwardly extending arm 66, which arm is provided with a plurality of adjusting apertures 67 for receiving the hooked end of the coil spring 68, whereby the coil spring may be held in an adjusted position. The drum supporting bracket 60 is provided with a transversely extending aperture 68' through which a pin 69 passes and this pin is held in an adjusted position by means of a plug 70, which plug passes through one of the adjusting apertures 71. The outer end 72 of the pin 69 is forked so as to straddle the coil spring as the main supporting shaft 5 is rotated. Through the medium of this adjusting pin 69, it will be seen that the tension of the spring may be regulated in view of the fact that as the drum supporting casing or bracket is rotated with the main supporting shaft 5 to such a position as to have the spring positioned within the forked end 72 of the pin 69, and a greater tension of the spring will be produced owing to the fact that the pressure will take place from the place where the forked end 72 of the pin 69 grips the spring 68, to the end 73 of the spring 68.

30 The side members 1 of the frame are provided with links or eyes 74 to which are attached chains 75, which chains are adapted to engage stakes 76 for bracing the frame while the loader is in operation. A guiding cable 77 is connected to one of the side members 1, by means of an eye 78 and this cable 77 is braced by means of a vertical brace 79, which brace is in turn braced by means of laterally extending rods 80, which rods are secured in the ground for preventing the lateral movement of the brace 79. A forwardly extending brace 81 is connected to the vertical brace 79 for preventing the brace 79 from swinging backward. A stop 82 is carried by the cable 77, and is adjustably secured thereto by means of a clamp for constituting means for limiting the distance which the horses are adapted to travel. A chain or strap 83 may be slidably mounted upon the cable 77, and may be provided with snaps for engaging the bits of the horses for holding the horses in alinement with the guiding cable 77. The usual double-trees 84 are carried by the cable and connected thereto by means of a pulley snap 85. The lifting cable 86 is in turn connected by means of this snap to the double-tree 84 for allowing the cable to be drawn with the team as the horses move away from the frame of the loader. It will be obvious that by means of this device, it will not be necessary to employ a driver, as the horses will be guided through the medium of this cable 77. The cable 86 passes over a pulley 87, which pulley may be adjustably secured at

different places along one of the diverging braces 6, to regulate the swing of the crane upon the main standard 5.

A depending link 88 is carried by the crane 17 and upon this depending link is 70 carried a block 89, over which the lifting cable 86 passes. This cable 86 passes longitudinally of the crane 17, and passes also over a pulley carried by the block 90 supported upon the rear end of the crane 17. 75 The lifting cable 86 passes over the pulley carried by the block 90, and in turn over the pulley 91 carried by the block 92. The cable then passes over a second pulley carried by the block 90, and is in turn connected to 80 the shaft 93 by means of a clamp. It will, therefore, be seen that as the horses travel away from the frame of the loader, the cable will be drawn outwardly thereby lifting the hay lifting fork 29 to the position as shown 85 in dotted lines in Fig. 1, and eventually lifting the hay loader so as to have the block 92 come in close proximity with the block 90, thereby allowing the fork to tilt by means of the apparatus hereinafter described.

A bell crank lever 94 is pivotally secured to the crane 17 near its rear end, and has a forwardly extending end 95. This bell crank lever 94 is provided with a swivel collar 96, and in this swivel collar is secured a rod 97. A nut is threaded upon each side of the swivel collar 96 for firmly connecting the rod 97 to the collar 96. A plurality of guide links 98 are connected to the crane 17, 100 and the rod 97 passes therethrough. A chain 99 is connected to the rear end of the rod 97, and passes over a pulley 100 carried by the crane, and over a second pulley 101 which pulley is carried by a vertical spring 105 plunger 102 carried by the collar 103, which collar cooperates with the supporting casting 11. The end of the chain 99 is connected to the crane 77 by means of an eye 104. The spring plunger 102 is carried within a casting 105, and is normally held in a downwardly forced position by means of a coil spring 106. The upper end of the supporting casting 11 is provided with ratchet teeth 115 for receiving the spring plunger 102, whereby the crane will be held against rotary movement upon the supporting casting 11 until the plunger or dog 102 is released from the ratchet teeth.

A ratchet releasing frame 107 is slidably mounted upon the rear end of the crane 17 so as to have a vertical sliding movement, and this ratchet releasing frame comprises a substantially inverted U-shaped structure having its side ends formed to constitute a substantially fan-shaped structure having a convex lower edge 108. Each of the side portions of the ratchet releasing frame 107 is provided with a vertically extending slot 109 in which travels the ends of the shaft 130

110 which support the pulley block 90. A laterally extending ear 111 is formed upon one of the side members of the ratchet releasing frame 107, and to this ear is connected a swivel head 112 in which works the arm 95.

The pulley block 92 comprises a substantially U-shaped frame 110, which frame carries a swivel connector 114 for attaching 10 the eye 33 to the pulley block 92. The upper ends of the sides of the block 92 are flared laterally to support a circular band 115 which circular band is adapted to engage the lower convex face 108 of the 15 ratchet releasing frame whereby the bell crank lever 94 will be swung so as to pull the rod 97 rearwardly thereby raising the dog or plunger 102 out of engagement with the ratchet teeth formed upon the supporting casting 11. Of course, as the horses 20 continue to pull upon the lifting cable 86, the crane 17 will then be rotated to the desired point where the hay is desired to be dumped from the lifting fork 29. It will 25 be seen that since the band 115 is made circular, the device will operate effectively no matter if the pulleys and supporting cables should become twisted. A cap 116 is carried by the block 92, and is provided with a 30 notched surface for taking the twist out of the rope as the same passes from one pulley to the other. A projecting arm 117 is carried by one of the side members 1, and is braced by means of a brace 118 and to this 35 arm 117 may be attached a stake for preventing the frame of the loader from dipping over as the ground is swung upon the opposite side of the machine.

The automatic trip regulator comprises a 40 frame 119, which frame extends vertically of the main frame of the hay loader, and is provided with an aperture through which the regulating rack bar 129 passes. The lower end of the frame 119 is provided with 45 a rearwardly extending portion 121 having an upturned end 122. An enlarged head 123 is carried by a bolt 124, which bolt passes through one of the diagonally extending braces 6 for firmly anchoring the 50 frame 119 to the main frame of the hay loader. A plunger rod 125 is connected to the head 123, and passes through the upwardly extending end 122 of the frame 119, and around this plunger 125 is coiled a coil 55 spring 126 for constituting a cushion for preventing the severe jar to the automatic trip regulator after the crane has been swung to the desired position. An auxiliary plunger 127 is secured to the frame 119, and passes through the depending end 128 60 of the automatic trip rack bar 129. A coil spring 130 is wound upon the auxiliary plunger rod 127, and constitutes means for normally holding the automatic trip regulator rack bar 129 in the position as shown

in Fig. 12, which is the position the rack bar 129 takes when the device is ready for action. The rearwardly extending portion 121 of the frame 119 is longitudinally slotted for allowing the frame to move longitudinally of the diagonally extending brace 6, and allow the spring 126 to actuate. 70

The regulator rack bar 129 is provided near its forward end with a longitudinally extending groove 131, and within this groove 131 is mounted an inclined lifting member 132. This lifting member 132 is provided with a depending lug 133 which passes through an aperture formed in the rack bar 129. Several of these apertures 80 134 are formed in the rack bar for holding the inclined lifting member in an adjusted position. A channel 135 is formed longitudinally of the rack bar 129 near one edge thereof, and within this channel is formed 85 a plurality of ratchet teeth 136. A smooth channel 137 is formed upon the upper face of the rack bar 129 so as to extend parallel with the channel 135, and the inner end of this channel 137 communicates with the 90 channel 135 as indicated at 138. An elevating cam member 139 is secured to the rack bar 129, by means of a cotter-pin 140, and this cam member is provided with a downwardly inclined lip 141 for directing 95 the outer end of the pawl 142 up out of the channel 135. The upper head of the cam member 139 is formed to constitute a cam 143 whereby when the pawl is raised up out of the channel 135, the pawl will be shifted 100 over into the channel 137, since the cam portion 143 extends over the top of both channels so as to direct the pawl from one channel to the other. It will be seen that as the 105 rack bar is then drawn to its normal position the pawl will ride back through the channel 137 and assume its normal position as illustrated in Fig. 13, through the medium of the spring 130, which will return the rack bar 129 to its normal position. A 110 transversely extending rib 144 is formed upon the rear of the cam member 139, and fits in a notch 145 extending transversely of the rack bar 129. This will facilitate the holding of the elevating cam member 139 115 in its correct locked position.

A series of apertures are formed along the rack bar 129 to allow the elevating cam member 139 to be adjusted to several positions along the line of the rack bar to control the amount of swing of the crane 17. A ratchet pawl 142 is carried by the frame 119 and is provided with a pair of side arms 147, which arms are connected to the frame 119 in such a manner as to allow the projecting tooth engaging portion 148 to swing from one channel 135 to the other channel 137. One of the arms 147 is longer than the other, and is provided with a longitudinally extending slot for allowing this swinging 130

movement. An enlarged portion 149 is formed upon the ratchet pawl 146 and through this enlarged portion passes a vertically extending rod 150, which rod carries at its upper end an adjusting thumb screw 151. The lower end of this rod 150 passes through an extension 152, and a coil spring 153 is carried by the lower end of the rod 150. This spring will allow a slight yielding movement of the lower pawl 154. The lower pawl is of a substantially U-shaped structure having a pair of parallel arms 155, which arms extend upon each side of the frame 119. The pawl 154 is provided with a transverse portion 156, which portion is adapted to engage the ratchet teeth 157 formed upon the lower face of the rack bar 129. A guiding bracket 158 is formed upon the side of the frame 119 to limit the swinging movement of the pawl 154. It will be seen that as the rack bar 129 is moved within the casing 119 to such an extent as to cause the pawl 142 to be raised by means of the elevating cam member 139, and the latch or pawl 154 will engage the ratchet teeth 157, and cause the same to be locked against any further inward movement upon the frame 119. However, as soon as the pawl 142 is thrown over into the channel 137, and the pawl 154 is kicked out of engagement with the channel 137, the pressure of the spring 130 will cause the pawl 154 to be moved out of engagement with the rack 157, and allow the rack bar 129 to assume its normal position.

The operation of the device is as follows: The frame of the machine is anchored by means of the stakes described previously, and as the hay is loaded upon the fork, the horses or draft animals are driven forward away from the frame of the hay lifter, thereby pulling upon the lifting cable 86, and causing the fork to rise so that the band 115 will engage the lower end of the frame 107. In this manner the bell crank lever 94 will be operated raising the plunger 102 out of engagement with the ratchet teeth formed upon the upper end of the supporting casting 11, and as the horses continue to pull upon the cable 86, the crane 17 will be revolved to the desired position. As the main standard 5 is rotated, the roller 59 will ride upon the inclined plane or lift member 132, thereby causing the rod 55 to be drawn downwardly and the catch or pawl 52 to be released from the sliding head 44. The head 44 will then slide down upon the shaft 45 and cause the cable 40 to yield thereby allowing the fork to tip by swinging upon the journal 35. As soon as the weight is released from the fork the spring 51 will cause the head 44 to return to its normal position as shown in Fig. 4, and be reengaged by the catch or dog 52. At the time the main standard 5 is rotated, the coil spring 68 will be expanded, and will come in engagement with the forked head 72 of the pin 69, as above described. The spring 68, as soon as the pressure is relieved from the lifting cable 86 will cause the supporting standard to return to its normal position.

For the reason that it often becomes necessary to dump the hay at different points rather than dumping the same at one point for facilitating the even distribution of the hay in its delivered condition, I have provided an automatic trip regulator, as above described and illustrated in Figs. 11 and 12. The elevating cam member which constitutes a means for limiting the distance of the dumps, as illustrated clearly in Fig. 13 and is operated as previously described. The first dump will take place on the line indicated by A, the second dump will take place on the line indicated by B, and the third dump will take place on the line indicated by C. The drum 62 is provided with a pin 169 for holding the cable 64 in engagement with the drum. A locking pawl 170 is carried by the drum supporting casing or bracket 60, and engages the notches 171 formed upon the shaft which supports the drum 62. As the main supporting standard 5 is rotated, and the arm 46 is swung, thereby causing the rack bar 129 to be slid through the frame 119, the ratchet pawl 142 will ride over one of the ratchet teeth 136 formed in the rack bar 129 thereby causing the ratchet pawl 154 to engage one of the ratchet teeth formed upon the lower face of the rack bar 129 and locking the rack bar 129 in its sliding movement through the frame 119. It should be understood that as the arm 46 is swung the same will engage the depending portion 133 of the lifting member 132 thereby causing the rack bar 129 to slide longitudinally of the frame 119. As soon as the stop occurs, the suddenness of the jar will be taken up by means of the spring 126, which is wound upon the plunger 125. After the hay has been dumped in the manner previously described, the main supporting standard 5 will rotate to its normal position, and the frame 172 will come in engagement with the rear ends 155 of the pawl 154, and cause the same to be raised and kick the tooth engaging portion 156 out of engagement with the ratchet teeth 157. The device will then be ready to take the next load of hay and upon dumping the next load will be dumped a little in advance of the first load, owing to the fact that the fork will not be tilted until the rack bar 129 has swung the distance of two notches or teeth 136, owing to the fact that the pawl 142 will then engage the tooth 173 as indicated in Fig. 12. The same operation will continuously follow from one to another according to the position in which the elevating cam member 134 is placed. As soon as

the last notch has been passed by the pawl 142, the pawl 142 will be swung to its original position as illustrated in Fig. 12 through the medium of the return slot 137 previously described.

Of course, it should be understood that this invention is susceptible of changes in its mechanical details of construction without departing from the spirit of the invention.

10 It should be understood that the pawl 154 is adapted to prevent the rack bar 129 from being drawn back to its normal position by means of the spring 130 as the rack bar is 15 being advanced for engagement with the pawl 142. When the sliding shoe 155' is moved longitudinally of the rack bar 129 so as to cause the ears 156' to be brought into engagement with the under face of the 20 rear ends 155 of the pawl 154, the pawl 154 will be kicked out of engagement with the ratchet teeth 157 formed on the lower face of the rack bar 129, therefore, allowing the spring to pull the rack bar 129 rearwardly. 25 The position of the sliding shoe 155' is clearly shown in Fig. 12 ready to kick the pawl 154 out of engagement with the ratchet teeth 157 formed upon the lower face of the rack bar 129.

30 What is claimed is:—

1. A machine of the class described comprising a frame, a main supporting standard, a crane, a hay lifting fork associated with said crane, means for raising said hay lifting fork, a bracing cable connected to said fork for holding the same in an operative position, an auxiliary supporting standard associated with said main supporting standard, a clamp engaging said main supporting standard and said auxiliary supporting standard, a latch member carried by said clamp, a sliding head slidably mounted upon said auxiliary supporting standard, a coil spring supporting said sliding head, said brace cable connected to said vertical sliding head, a vertical rod adjustably secured to said latch member, said latch member engaging said sliding head for holding said sliding head in a locked position, a lever connected to the lower end of said rod, and means coöperating with said lever for raising the outer end thereof and causing said rod to be pulled downwardly whereby said latch will be released from 55 said sliding head and said sliding head will travel upon said auxiliary supporting standard for causing said fork to be dumped as the main supporting standard is rotated.

2. A machine of the class described comprising a frame, a main supporting standard, a crane, a hay lifting fork, means for lifting said hay lifting fork, a bracing cable coöperating with said hay lifting fork, said bracing cable passing longitudinally of said 65 main supporting standard, means for yield-

ably connecting the inner end of said bracing cable, locking means for holding said inner end of said bracing cable in a set position, a lever coöperating with said means for holding said cable in a locked position, 70 said lever provided with a roller at its outer end, a rack member carried by said frame and provided with an inclined lifting member adapted to be engaged by said roller of said lever when said main supporting standard is rotated whereby said locking means will be released and said hay fork will be dumped.

3. A machine of the class described comprising a frame, a main standard, a crane, a 80 hay lifting fork, means for raising said hay lifting fork, means for swinging said crane and rotating said main supporting standard, an arm carried by said main supporting standard and rotated therewith, a rack 85 member carried by said frame, means for dumping said hay lifting fork, said arm coöperating with said rack member for swinging the same upon said frame, and ratchet means coöperating with said rack member 90 for controlling the dumping of said hay lifting fork.

4. A machine of the class described comprising a frame, a central main supporting standard, a crane carried by said supporting standard, a hay lifting fork carried by said standard and coöperating with said crane, means for raising said hay lifting fork, dumping means coöperating with said hay lifting fork, means for actuating said 100 dumping means, a tripping arm carried by said main supporting standard, a lever carried by said tripping arm, and coöperating with said tripping means, a rack member carried by said frame, said lever passing 105 over said rack member and said tripping arm passing under said rack member, an inclined tripping member carried by said frame, a depending lug carried by said rack member adapted to be engaged by said tripping arm for causing said rack member to be swung upon said frame, spring means for returning said rack member to its normal position after being released from said tripping member, a guiding frame supporting 110 said rack member, means yieldably supporting said guiding frame upon said first-mentioned frame for relieving the strain from said rack member after the same is swung to its full extent, a ratchet mechanism carried 115 by said rack member for limiting the swinging of said rack member upon said first-mentioned frame, and ratchet means coöperating with said rack member and said first-mentioned ratchets for causing said 120 ratchets to assume their normal position after the fork has gone through a series of dumps.

5. A machine of the class described comprising a frame, a central supporting stand- 125

ard, a crane, a hay lifting fork carried by said central supporting standard, means for raising said hay lifting fork, means for holding said hay lifting fork in a set position, means for releasing said hay lifting fork and allowing the same to dump, a tripping arm carried by said main supporting standard, a lever carried by said tripping arm, and coöperating with said hay lifting fork for limiting said hay lifting fork when said lever is actuated, a rack member carried by said frame and passing between said tripping arm and lever, an inclined tripping member carried by said rack member and capable of swinging said lever for allowing said hay lifting fork to dump, means carried by said rack member and capable of being engaged by said trip arm for causing said rack member to be swung, a supporting frame engaging said rack member, said supporting frame provided with a rearwardly extending portion, a spring bumper engaging said supporting frame for yieldably supporting the same upon said first-mentioned frame, said rack member provided with a channel having ratchet teeth formed therein upon the upper face thereof, a ratchet member carried by said rack member and consisting of a substantially U-shaped structure having a forwardly extending ratchet tooth engaging lip, said ratchet member capable of being swung laterally relative to said rack member, said rack member provided with a return channel formed parallel with said ratchet channel and communicating at its inner end with said ratchet channel, a lifting member adjustably mounted in said ratchet channel for throwing said ratchet member into said return channel at a determined time, a locking ratchet carried by said frame, ratchet teeth formed upon the under face of said rack member, said last-mentioned ratchet member engaging said ratchet teeth formed upon the under face of said rack member, and means connecting said ratchet members for causing the same to alternately engage their respective teeth in said rack bar for limiting the swing of said crane upon said main standard.

6. A device for controlling the dumping of a hay fork comprising a frame, a supporting frame, a rack bar, said rack bar provided with a pair of parallel channels, one of said channels provided with ratchet teeth formed therein, the other of said channels constituting a return channel and communicating at its inner end with the other channel, a shifting cam adjustably secured to said rack member and provided with an inclined portion, a ratchet pawl carried by said supporting frame and traveling in said channels, said ratchet pawl provided with a tongue adapted to ride upon said inclined plane, said shifting cam provided with a curved surface overhanging the return channel and capable of swinging the tongue of said ratchet pawl into said return channel, a locking pawl carried by said supporting frame, ratchet teeth formed upon the under face of said rack bar, means connecting said locking pawls for causing said last-mentioned pawl to engage the teeth upon the under face of said rack bar as said first mentioned locking pawl rides upon the teeth upon the upper face of said rack bar whereby said rack bar will be advanced, the distance of the length of one tooth upon the upper face of said rack bar at each time, the hay fork is dumped, and means adapted to engage said ratchet pawl coöperating with the teeth upon the under face of said rack bar for releasing the same from said teeth at each time the dumping fork is brought to its normal position.

7. A machine of the class described comprising a frame, a main standard, a crane, a hay lifting fork, and automatically adjustable means coöperating with said hay lifting fork and said main standard for causing said hay lifting fork to selectively dump at different points at a predetermined time.

8. A machine of the class described comprising a main frame, a main standard, a crane, a hay lifting fork carried by said crane, means for raising and lowering said hay lifting fork, and automatically adjustable means for causing said hay lifting fork to dump at different points during a series of dumping operations.

In testimony whereof I hereunto affix my signature in presence of two witnesses.

RAYMOND J. FRANCIS.
